(57) **CLAIM**

The ornamental design for an icon for a portion of a display screen, as shown and described.

DESCRIPTION

FIG. 1 is a front view of an icon for a portion of a display screen showing my new design; and,

FIG. 2 is a front view of an icon for a portion of a display screen showing an alternative embodiment of my new design.

The broken line showing of the portion of a display screen is for illustrative purposes only and forms no part of the claimed design.

1 Claim, 2 Drawing Sheets

FIG. 1

FIG. 2
